ERVIN N. CESAR, OF PONCA CITY, OKLAHOMA.

CRANKING MECHANISM FOR EXPLOSIVE-ENGINES.

1,328,127.

Specification of Letters Patent. Patented Jan. 13, 1920.

Application filed April 12, 1919. Serial No. 289,624.

To all whom it may concern:

Be it known that I, ERVIN N. CESAR, a citizen of the United States, and a resident of Ponca City, in the county of Kay 5 and State of Oklahoma, have made certain new and useful Improvements in Cranking Mechanism for Explosive-Engines, of which the following is a specification.

My invention relates to a cranking device 10 for starting explosive engines and has for an object to produce an improved cranking mechanism which is not liable to cause injury to the operator by preventing careless or incorrect use.

Another object is to produce a device 15 which, if the crank should kick back as a result of premature explosion, or back-fire, injury to the operator will not ensue.

With these and other objects in view my 20 invention consists in certain novel features of construction, arrangement and combination of parts as will be hereinafter fully described and pointed out in the claims, reference being had to the accompanying drawing, in which:

Figure 1 is a vertical longitudinal section of the device;

Fig. 2 is a front elevation of same;

Fig. 3 is a vertical transverse section on 30 line 3—3 of Fig. 1;

Fig. 4 is a similar section on line 4—4 of Fig. 1;

Fig. 5 is a vertical transverse section showing position of parts when cranking shaft 35 and crank sleeve are freed from each other;

Fig. 6 is a side elevation showing means for limiting movement of tripping wheel;

Fig. 7 is an elevational view looking at the front of Fig. 6.

Referring more particularly to the drawings 40 10 indicates the usual cranking shaft having the usual clutch member 11 at its rear end which is used to couple with a mating clutch member on the forward end 45 of the motor shaft usual in this type of motors. The forward end of the crank shaft is provided with a vertical slot or mortise 12 in which is pivoted an elongated and relatively thin latch or bolt 14, said bolt being normally forced upwardly by a plate 50 spring 15, one end of which is secured to the shaft 10 at 16 and the other end of such spring being secured to the bolt 14 at 17.

Mounted on the crank shaft 10 is a sleeve 55 18 having a circular bore and which abuts at its rear end a collar 19 on shaft 10, said

sleeve having a longitudinal opening 20 through which the latch 14 may be projected. On the forward end of the crank sleeve 18 a crank handle 21 is held against rotation by means of the key 22 seated in key-seats in the ring member 23 of handle 21 and in the end of the sleeve 18. The crank handle is held on the crank sleeve against longitudinal movement by a nut 23a.

The crank shaft 10 is supported in a bracket 24 rigidly secured to the front of the automobile by screws or bolts and usually at the front of the radiator, and is held in proper alinement by the bearing 25 projecting forwardly from the bracket 24. Projecting forwardly and upwardly from the bracket bearing 25 is a bracket arm 26 having pivotally secured to its free end a pawl 27, the purpose of which later appears.

Mounted on the crank sleeve 18 and capable of rotation thereon under force, is a tripping wheel or ratchet 28, having ratchet teeth 29 to be engaged by the pawl 27, the bore of the wheel being eccentric, the inner 80 surface being struck on two different circles, which develops a spiral curve 30 and straight shoulder 31 joining the ends thereof. On the forward face of tripping wheel 28 is placed a lug 32 which may engage one side 85 of a stop projection 33 on the periphery of the crank sleeve 18, when the tripping wheel is partly rotated on the sleeve, as plainly seen in Figs. 6 and 7.

The shaft 10 is normally forced outwardly 90 by spring 34 surrounding the shaft between the outer end of bearing 25 and the collar 19, so that the shoulder 10a of the shaft is forced against the bracket 24 and the clutch member 11 held out of engagement with the 95 clutch member of the motor shaft.

The sleeve 18 has in a transverse slot immediately beneath the tripping wheel 28 which begins within the face of said sleeve as at 40 and extends across the sleeve for 100 about 180 degrees, the tapered portion 41 of this slot forming a seat to receive the cam surface 30 within the tripping wheel.

The normal position of the parts is shown in Fig. 1, the crank shaft 10 and sleeve 18 being coupled by the latch 14; the crank handle is now pushed inwardly whereupon all the parts move rearwardly against the spring 34 and cause the clutch element 11 to engage the clutch element of the motor 110 shaft.

The motor shaft can now be turned as in

the ordinary manner. If, however, the motor shaft is suddenly turned back or reversed by back-firing, kicking or otherwise, the pawl 27 is lodged against a tooth of the 5 tripping wheel, and as the pawl itself is held on a stationary part of the machine the tripping wheel is caused to slip or turn clockwise around the sleeve in a direction opposite to the direction of rotation of the shaft 10 until stop 32 engages stop 33; in this reverse movement of the shaft the cam surface 30 of the tripping wheel, bears against the latch 14 and forces it inwardly until it occupies the position shown in Fig. 5 in which 15 position the shaft is then free to turn within the sleeve 18 to which the handle is applied; and consequently the handle is not reversed or "kicked back" as the movements referred to are practically instantaneous. 20 The trip wheel may then be restored to its normal position by spring means 50, a coiled spring, one end of which is fastened to the trip wheel, and the other end to the sleeve 18. 25 From the above it will be seen that I provide a simple cheap and efficient cranking means and one which is perfectly safe in use and overcomes the danger of injury from back-firing or "kicking" of motor.

30 I claim:—

1. In a cranking device for explosive engines, the combination with an engine shaft, of a slidably and rotatably mounted cranking shaft, clutch means for periodically coupling said shafts, a cranking sleeve rotatably mounted on said cranking shaft, a spring actuated latch carried by said shaft and the said shaft and sleeve locked together against rotary movement, a tripping wheel mounted 35 on said sleeve and adapted to have a certain rotary movement thereon, a stationarily held pawl engaging said tripping wheel against rotation in one direction upon reverse rotation of the cranking shaft, and 40 cam means within the tripping wheel adapted to withdraw the aforesaid latch from the cranking sleeve and permit reverse rotation of the cranking shaft within the crank sleeve.

2. In a starting device for explosive engines, the combination with the engine shaft, of a rotatably mounted and endwise sliding starting shaft, a transversely movable spring-actuated latch mounted in the shaft, a crank sleeve mounted on said shaft, and 55 having a slot to receive said latch, a ratchet wheel rotatably mounted on said sleeve, cam means within the ratchet wheel coacting with said latch to retract same from the slot of the crank sleeve, and means for normally 60 restraining the ratchet wheel against rotation in one direction.

3. A safety crank device, comprising a slidable clutch shaft formed with a mortise therethrough, a spring actuated latch 65 mounted to swing in said mortise, a sleeve mounted on said shaft and adapted to rotate with, and also independent of said shaft, said sleeve having a slot therethrough to receive said latch, a tripping wheel 70 mounted on said sleeve, cam means carried by said tripping wheel, to retract said latch from the sleeve, coactive means carried by the sleeve and tripping wheel to lock same together for simultaneous rotation in one 75 direction, a handle rigidly secured to said sleeve, and stationary means for permitting rotation of the tripping wheel in one direction and holding same against rotation in opposite direction.

4. A cranking device for explosive engines comprising a slidable and rotative crank shaft, a clutch element at its inner end, a slotted cranking sleeve, a transverse mortise in the crank shaft, a spring actuated 85 plunger mounted in said mortise and adapted to project through the slot of the sleeve, a tripping wheel mounted on said sleeve and having an eccentric bore adapted to retract the said plunger upon rotation of the tripping wheel in one direction and means engaging said tripping wheel to hold same against rotation in one direction and to permit its slipping in the opposite direction around the sleeve upon reverse rotation 90 of the crank shaft.

ERVIN N. CESAR.
